N°. 1,028.

G. W. Smith's Design for Pitchers.

Patented July 20, 1858.

Fig. 1.

Fig. 2.

Des. 1028

Geo W. Smith, of Hartford, Conn.
Letters Patent No. 1028 - dated July 20, 1858.

The schedule referred to in these Letters Patent and making part of the same.

To all whom it may concern:

Be it known that I, G. W. Smith, of Hartford, in the County of Hartford, and State of Connecticut, have produced a new and Ornamental Design for Ice and other Pitchers, and I do hereby declare that the following is a full, clear and exact description of the same, being had to the annexed drawings of the same, making part of this Specification.

Figure 1. is a side elevation of a triple wall Ice Pitcher, formed after the improved design.

Figure 2. is a horizontal section of ditto.

Similar letters in the figures refer to corresponding parts.

The novel features of this design consists in producing an ice or other pitcher of symmetrical configuration and exterior embellishment as shall harmonize in character and present a simple, artistic and ornamental appearance.

The base A, of the pitcher is formed somewhat after the manner of the Scotia and upper half of the torus of the composite order of architecture, the lower portions of these adornments being provided with alto-relievo semi-spherical dentils B, of such relative size as to properly embellish and relieve the plainness of this portion of the pitcher.

The bulging portion of the body . . . . . of the pitcher, extends outward and upwards from this base, in curved lines somewhat similar to the curves of cima-reversa's and cima-recta's combined, the lower bulging curve being shorter and more abrupt and rounded than the upper one, which extends therefrom in a long and graceful curve, in a similar relation to the same as the upper curve of a cima-recta is to the lower one, except that being a greater sweep a better finish and more symmetrical form is given the general configuration of the several parts.

The sides of the pitcher are embellished with a series of flutes C, and convex ridges D, running one into the other and forming, when combined . . .

cima - novices and cima - rectas which terminate at their upper and lower ends in embossed scroll work E, somewhat resembling the German quatrefoil above, and the trefoil below. The flange F, and sprout G, and handle H, are shaped in the usual manner, and the former are decorated on their edges with alto-relievo semi-spherical or oval shaped projections, and the latter with embossed work, representing folding leaves.

The cover I, is surmounted with a top piece K, representing a vine - stem rising from the apex, and terminating above with a suspended leaf. From branches curving outwardly from this stem are suspended two branches of grapes, while a series of additional leaves and bunches of grapes are displayed gracefully in alto-relievo over the upper surface of the cover, in such a manner as to give a crowning adornment to the pitcher, in keeping with the general configuration and decorations of its base, body and handle.

What I claim as new and desire to secure by Letters Patent, is,

Giving ice and other pitchers the configurations, flutings, embossings and embellishments before described, so as to produce a new and ornamental design symmetrical in its character and of a chaste and harmonious appearance.
